UNITED STATES PATENT OFFICE.

BENJAMIN LIEBOWITZ, OF PENNSIDE, PENNSYLVANIA, ASSIGNOR TO S. LIEBOWITZ & SONS, INC., A CORPORATION OF NEW YORK.

COLLAR-BAND STRETCHER.

Application filed October 11, 1924. Serial No. 743,165.

To all whom it may concern:

Be it known that I, BENJAMIN LIEBOWITZ, a citizen of the United States, residing at the village of Pennside, county of 5 Berks, and State of Pennsylvania, have invented a certain new and useful Improvement in Collar-Band Stretchers, of which the following is a specification.

This invention relates to an improved 10 stretcher for shirts having collar-bands.

The object of the invention is to provide a quickly operable device whereby such shirts may be held upon a table in proper position to be ironed. With my improved stretcher 15 both hands of the operator are left free for use in ironing and handling the shirt.

I attain this object, as well as others, by means of the novel features of construction, arrangement, and combination of parts here- 20 inafter described and set forth in the claims.

A preferred embodiment of the invention is illustrated in the accompanying drawings, forming a part of this specification, and in which:

25 Figure 1 is a plan view of the improved stretcher, partly expanded, applied to a shirt laid out in position to be ironed, and indicating the fully expanded position of the stretcher in dotted lines;

30 Fig. 2 is a plan view of the stretcher with its arms in closed position, and,

Fig. 3 is a side view of the device.

In the drawings, 1 indicates an ironing table having a standard 2 suitably affixed 35 thereto. A stud 3 projects from the standard and carries a hinge piece 4 on which the stretcher is supported. The hinge 4 permits of swinging the stretcher from its vertical inoperative position, indicated by the dotted 40 lines in Fig. 3, to its horizontal operative position shown in full lines in said view.

The stretcher comprises a pair of arms 5-6 pivoted at 7 to the horizontal leaf of the hinge 4. The outer end of arm 5 is 45 pivoted at 8 to a collar 9, which collar carries a rod 10 having an enlarged head. The outer end of the other arm 6 is pivoted at 11 to a sleeve 12 sliding on the rod 10.

Extending forward from the collar 9 and 50 the sleeve 12, respectively, are the right angle pieces 13 and 15. The vertical members of these pieces carry at their feet the plates 14 and 16, respectively, which plates are adapted for insertion in the shoulders 55 of the shirt adjacent the collar-band, as in-

dicated by the dotted lines in Figure 1 of the drawings.

Links 17 and 18 pivotally connect the parts 13 and 15 with the hook 19 which latter serves as a handle for the stretcher. 20 60 is a helical spring attached at its ends to the pivot pin 7 and the hook 19, respectively.

21 is a pin fixed to the horizontal portion of the member 15 and projecting through a hole in the corresponding portion of the 65 member 13. 22 is a similar pin affixed to the member 13 and passing through a hole in the member 15. When the arms of the stretcher are in their closed position, shown in Figure 2, the friction of the parts is sufficient to maintain them in such position. 70 Slight pressure in opposite directions on the pins 21-22 will cause the members 13 and 15 to separate and will permit the spring 20 to operate to retract and spread 75 said members.

A spring clip 23 is provided to engage and hold the stretcher when it is swung into its vertical position, said clip being supported on a vertical extension of the standard 2. 80

In using the device, a former 24, made of a thin band of brass or other resilient material, is placed in the collar-band 25 of the shirt 26. The stretcher with its arms closed as shown in Fig. 2, is then swung 85 down so that its plates or fingers 14-16 come within the former 24. The pins 21-22 are now pressed towards each other to open the arms of the stretcher as indicated in Fig. 1. The opening movement of the stretcher causes the members 13 and 15 to spread apart so as to press against opposite parts of the former 24, thereby expanding the latter against the collar-band 25 to hold it in shape; and to slide the plates 90 or fingers 14-16 into the shoulders of the shirt, as shown in the dotted lines in Fig. 1, so as to hold the shirt in place on the ironing table. A weight or clamp (not shown) may then be applied to the tail of 100 the shirt to maintain it in its stretched position during the ironing operation.

Various changes and modifications in the details of construction and arrangement of parts herein described may be made without 105 departing from the scope of the invention.

What I claim is:

1. A device of the character described comprising a support, a pair of arms pivoted to the support, a pair of plates each adapted 110

for insertion into the shoulder of a garment, means carried by said arms for supporting and guiding the plates, and a spring acting on said means to move the plates in opposite directions.

2. A device of the character described comprising a support, a pair of arms having their inner ends pivoted to the support, a collar pivoted to the outer end of one of the arms, a guide rod fixed to the collar, a sleeve slidable on the rod and pivoted to the outer end of the other arm, the collar and the sleeve each having a forward extension, plates carried by the extensions in position for insertion into the shoulders of a garment, a toggle connecting said extensions, and a spring acting on the toggle joint to move the plates in opposite directions.

3. A device of the character described comprising a hinged support, a pair of arms, a pin pivotally connecting the inner ends of the arms together and to the support, a collar pivoted to the outer end of one of the arms, a guide rod fixed to the collar, a sleeve slidable on the rod and pivoted to the outer end of the other arm, the collar and the sleeve each having a forward extension, plates carried by said extensions in position for insertion into the shoulders of a garment, a handle for the device, a pair of links having their outer ends pivotally connected together and to the handle and having their inner ends pivoted to the extensions of the collar and the sleeve respectively, and a spring secured at its ends to the handle and the pivot pin.

BENJAMIN LIEBOWITZ.
